SINKER

Arthur F. Andrews, 115 Pleasant Hill Road,
Pleasant Hill, Calif.

Filed Nov. 13, 1961, Ser. No. 67,479

Term of patent 14 years

(CL. D31—4)

The broken lines shown in FIGS. 1 and 2, but omitted in FIG. 3, are for illustrative purposes only.

I claim:

The ornamental design for a sinker, as shown and described.
